UNITED STATES PATENT OFFICE.

JOSEPH GOULBOURN AND HARRY HARDY JACKSON, OF LEICESTER, ENGLAND,
ASSIGNORS TO UNITED SHOE MACHINERY CORPORATION, OF PATERSON, NEW
JERSEY, A CORPORATION OF NEW JERSEY.

BUTTONHOLE-SEWING MACHINE.

Application filed March 16, 1920. Serial No. 266,398.

To all whom it may concern:

Be it known that we, JOSEPH GOULBOURN and HARRY HARDY JACKSON, subjects of the King of Great Britain, of Leicester, residing at Leicester, England, have invented certain new and useful Improvements in Buttonhole-Sewing Machines; and we do hereby declare the following to be a full, clear, and exact description of the invention, such as will enable others skilled in the art to which it appertains to make and use the same.

The invention relates to buttonhole sewing machines and more particularly to means by which the length of the buttonholes sewn may be varied.

The invention is intended primarily to provide mechanism by which variations in the length of the buttonhole may readily be secured in machines such as shown and described in Patent No. 1,063,880, June 3, 1913, in which the stitch forming mechanism and work clamp are given a relative movement, both lengthwise and laterally of the buttonhole, and in which the stitch forming mechanism is rotated in sewing about the end or ends of the buttonholes.

In the machine of the above patent the work is moved lengthwise of the buttonhole from cutting to sewing position, and also during the sewing by a feed cam having a definite throw, and the sewing mechanism is started and stopped at definite points in the rotation of the cam so that the cam will be in proper time with the cams and mechanisms which move the clamp laterally, and rotate the stitch forming mechanism in sewing about the eye and bar end of the buttonhole. In embodying the invention in this machine provision is made for varying the ratio between the traveling movements of the clamp before and during the sewing while the points in the rotation of the feed cam at which the sewing begins and ends remain the same for all lengths of buttonholes. This variation may be secured by change in the travel given the work clamp by that part of the cam which moves the clamp during the sewing or by change in the travel given the clamp by that part of the cam which moves the clamp when the sewing mechanism is idle, or by inverse or differential variation of both these travels.

In embodying the invention in a mechanism which may readily be applied to the

machine of the above patent the requisite variation in the ratio of the travels is preferably secured by the provision of means which, during one part of the travel of the work clamp, supplements, and during another part reduces the travel due to the feed cam. This means may be, and preferably is, in the form of an adjustable turret, or disk, provided with a number of cams, any one of which may be brought, by adjustment of the disk, into position to act upon the connections between the feed cam and the work clamp.

The features of the invention will be readily understood from an inspection of the accompanying drawings and the following detailed description of the mechanism illustrated therein. In the drawings Fig. 1 is a side elevation showing so much of a buttonhole sewing machine as is necessary to illustrate the application of the present invention thereto. Fig. 2 is a detailed plan view showing the connections between the feed cam and the swinging and sliding frame which carries the work clamp. Fig. 3 is a section on line 3-3 of Fig. 2, and Fig. 4 is a plan of the auxiliary cam.

The machine shown in the drawings is similar in general construction and mode of operation to the machine shown and described in the patent above referred to and is provided with sewing mechanism, the upper needle of which is indicated at 2, with a work clamp 4, with a cutter 6 for cutting the buttonhole slit, with mechanism indicated at 8 for starting and stopping the sewing mechanism at definite points in the rotation of a cam gear which carries the cams for operating the cutter and for feeding the work clamp lengthwise of the buttonhole. The machine is also provided with cams and connecting mechanism (not shown) for rotating the stitch forming mechanism and for moving the work clamp laterally when sewing about the eye and the bar end of the buttonhole.

In embodying the preferred form of the invention in this machine the sliding and swinging carriage or frame 10 which carries the work clamp is fed from buttonhole cutting position to sewing position, and is also fed during the sewing operation, by means of a horizontal lever 12 positioned in a recess 14 in the bed of the machine. A

short arm 16 of the lever is connected to the sliding frame 10 by a vertical pin 18, which acts as the pivot about which the frame 10 swings during the sewing round the eye and across the end of the buttonhole. The pin 18 passes through a guide-way 20 formed in the bed of the machine and has mounted upon it a block 22 which slides in the said guideway and controls the movement of the frame 10. At the junction of the short arm 16 of the lever and a second longer arm 24 approximately at right-angles to it, is an upstanding cam roll 26 which enters a cam groove 28 formed on the under face of the 15 cam-carrying gear wheel which is shown and described in the above mentioned patent. This cam groove is the customary one but is displaced angularly about its axis of rotation in view of the fact that the cam roll 26 engages it at a point offset from (instead of aligned with, as formerly), the pin 18 in the 20 sliding frame. At the end of the arm 24 of the lever is a second upstanding cam roll 30 arranged to enter one of a number of radial 25 cam tracks 32 (see Figure 4) formed in the under face of a cam disk or turret 34. The cam disk 34 has formed round its edge a similar number of radial slots 36, one of which engages a pin 38 projecting upwardly 30 from the bed of the machine. The edge of the disk 34 at a point approximately at right angles to the radial line of the slot engaging the pin 38 bears against a vertical face formed on a bracket 40 fixed by a clamp 35 screw 42 to the bed of the machine. The disk has formed in the centre of its upper face a conical recess 44 which is entered by the cone point of a thumb screw 46 which passes through an overhanging arm 48 of the bracket 40. The centre of the thumb 40 screw is slightly nearer to the pin 38 and face than the centre of the conical recess 44 when the slot and edge of the disk bear against the pin and face of the bracket and 45 therefore when the thumb screw 46 is tightened the cone point draws the disk against the pin and face and the disk is thereby correctly positioned. A fixed pointer 50 on the bracket and index marks 52 on the upper 50 face of the disk, indicate which cam track is in engagement with the roll 30.

The cam tracks 32 in the under face of the disk all lead into a central recess 54 in the disk and if the thumb screw 46 is unfastened 55 and the disk moved until the slot 36 is disengaged from the pin 38 and the cam roll 30 is in the central recess 54, the disk 34 may be turned and another cam track brought into engagement with the cam roll 30. The 60 disk will then be moved back into engagement with the pin 38 and face and the thumb screw 46 tightened. If during the feeding movement of the sliding and swinging frame 10 the lever 12 is swung about the centre 65 of the cam roll 26, the feed movement of

the frame will be accelerated or retarded according to the direction of the swinging movement and the feed movement may therefore be accelerated during part of the feeding movement and then retarded during 70 the rest of the movement or vice versa. If the feeding movement of the frame be retarded during its movement from cutting position to the point at which the sewing commences and is then accelerated during 75 the sewing, the length of buttonhole sewn will be longer than if the movement be first accelerated and then retarded, it being understood that the distance between the end of the eye of the buttonhole and the needle path, at the time of cutting the buttonhole, is maintained constant for all lengths of buttonhole. It may here be pointed out, however, that according to the invention the disposition just referred to is not essential in all 80 cases, since if at the time of cutting the buttonhole the position of the end of the buttonhole slit remote from the eye and nearer the needle path is kept the same for all 85 lengths of buttonholes a mechanism similar to that described may be used to influence the effect of the cam groove 28 only during 90 the sewing.

The cam 28 on the cam carrying gear wheel, above referred to, is arranged to feed 95 the sliding and swinging frame a suitable distance for a medium length buttonhole, and the cam track 32 in the disk 34 engaging the cam roll 30 at this time will be straight and radial and therefore during 100 the feeding movement of the frame no swinging movement of the lever 12 will take place and the feeding movement of the frame will be at a uniform rate. The other cam tracks in the disk 34 are arranged some 105 either first to accelerate and then retard the feeding movement in accordance with the needs of various shorter buttonholes or first to retard and then accelerate and to thereby determine the length of longer buttonholes. 110 All the cam tracks 32 in the disk are so arranged that the feed roll 30 is always on the same radial line of the disk (see Figure 4) at the beginning and end of the feeding movement and the frame will therefore always 115 feed to the same point and return to the same point. In addition, the cams 32 are so formed that the point on the work at which sewing is to commence is presented in the needle path always at the same time in 120 the rotation of the cam-carrying gear wheel.

What is claimed is:

1. A buttonhole sewing machine having, in combination, sewing mechanism, a work holder, actuating mechanism having a definite throw for causing a relative travel between the sewing mechanism and work holder, mechanism for starting and stopping the sewing mechanism at fixed points in the movement of the actuating mechanism, and 125

means for varying the ratio between the relative travel before, and the relative travel during, the operation of the sewing mechanism to vary the length of buttonhole sewed.

5 2. A buttonhole sewing machine having, in combination, sewing mechanism, a work holder, a feed cam for causing a relative travel between the sewing mechanism and the work holder, mechanism for starting and 10 stopping the sewing mechanism at fixed points in the rotation of the cam, and means for varying the ratio between the relative travel before and the relative travel during the operation of the sewing mechanism to 15 vary the length of buttonhole sewed.

3. A buttonhole sewing machine having, in combination, a buttonhole cutter, sewing mechanism, a work holder, a feed cam for moving the holder from cutting to sewing 20 position, and also during the sewing, mechanism for starting and stopping the sewing mechanism at fixed points in the rotation of the feed cam, and means for varying the travel given the work holder during the sewing 25 with relation to the travel given the work holder between cutting and sewing positions.

4. A buttonhole sewing machine having, in combination, sewing mechanism, a work 30 holder, a feed cam for causing a relative travel between the sewing mechanism and the work holder prior to and during the sewing, and an auxiliary means set by the operator in accordance with the length of the buttonhole to be sewed for supplementing the 35 action of the cam during a part of its rotation and reducing its action during another part of its rotation.

5. A buttonhole sewing machine having, 40 in combination, sewing mechanism, a work holder, a feed cam, a connection for transmitting motion from the cam to the work holder, and a secondary cam mechanism adapted to be set by the operator for acting 45 on said connection during the action of the feed cam to vary the result of said action in a manner determined by the operator.

6. A buttonhole sewing machine having, 50 in combination, sewing mechanism, a work holder, actuator for feeding the work holder, and a turret provided with a plurality of cams and adjustable to establish connection

between the actuator and one or another of said cams according to the character of the buttonhole to be sewed.

55

7. A buttonhole sewing machine having, in combination, a buttonhole cutter, sewing mechanism, a work holder, means for causing a relative travel of the sewing mechanism and holder between cutting and sewing positions and during the sewing, uniformly acting actuating mechanism for said means, and a control device readily interchangeable for another and acting on said means to vary the movement transmitted therefrom to the holder in accordance with the length of buttonhole to be sewed.

60

8. A buttonhole sewing machine having, in combination, sewing mechanism, a work 70 holder, a feed cam, a lever connected to move with the holder, and engaged by the cam, and a plurality of stationary cams, any one of which may be brought into position to act on the lever and modify the movements 75 transmitted from the feed cam to the holder in accordance with the length of buttonhole to be sewed.

9. A buttonhole sewing machine having, in combination, sewing mechanism, a work 80 holder, a feed cam, a connection for transmitting motion from the cam to the work holder, and a secondary cam for acting on said connection during the action of the feed cam to determine the movement transmitted 85 from the feed cam to the work holder.

10. A buttonhole sewing machine having, in combination, a buttonhole cutter, sewing mechanism, a work holder, a feed cam for causing a relative travel between the sewing 90 mechanism and work holder prior to and during the sewing, a connection between the feed cam and holder, and a secondary cam acting on the connection to determine the ratio between the travel during and prior to 95 the sewing.

11. A buttonhole sewing machine having, in combination, sewing mechanism, a work holder, a feed cam, a lever connected to move with the holder and engaged by the cam, 100 and a stationary cam, acting on the lever to modify the movements transmitted from the feed cam to the holder.
